RAILWAY SWITCH AND SIGNAL MECHANISM.

No. 878,666.

Specification of Letters Patent.

Patented Feb. 11, 1908.

Application filed September 21, 1907. Serial No. 393,926.

To all whom it may concern:

Be it known that I, JOHN S. PAYNE, citizen of the United States, residing at Mulvane, in the county of Sumner and State of Kansas, 5 have invented certain new and useful Improvements in Railway Switches and Signal Mechanisms, of which the following is a specification.

This invention contemplates certain new 10 and useful improvements in railway switch and signal mechanism and relates particularly to pneumatic actuating means for the switch or signal, embodying a pump and improved connection between said pump, the supply tank, the controlling valves, and the switch or signal mechanism, the pump being arranged to be actuated by the passage of a train over that portion of the track where the pumping mechanism is located.

20 The invention consists in certain constructions, arrangements and combinations of the parts that I shall hereinafter fully describe and then point out the novel features in the appended claims.

25 For a full understanding of the invention, reference is to be had to the following description and accompanying drawings, in which:

Figure 1 is a sectional side elevation illustrating my improvements in switch and signal mechanism; Fig. 2 is an enlarged side elevation partly in section of the signal apparatus; Fig. 3 is a top plan view of a portion of the apparatus arranged to operate the 30 switch; Fig. 4 is a transverse sectional view of the switch mechanism; Fig. 5 is a detail perspective view of a switch locking bar employed; Fig. 6 is a detail view of a clamp designed to secure the said locking bar in place; Fig. 7 is a side elevation of the said clamp; Fig. 8 is a detail sectional view of the governing valve; Fig. 9 is a side elevation, partly in section of a modified arrangement of signal mechanism; and, Fig. 10 is a detail transverse section taken through the rail at the point of connection of the pump actuating bar thereof.

Corresponding and like parts are referred to in the following description and indicated in all the views of the drawings by the same reference characters.

My invention comprises an air pump 1 in

which the follower head or piston 2 is mounted, the stem or plunger rod 3 of said piston being designed to pass upwardly from the 55 pump, as clearly illustrated in the drawings. The pump 1 may be secured to any two adjacent cross ties 4 by means of the lower or upper plates 5 and 6 that are bolted to the ties as shown, the plunger rod 3 extending 60 upwardly through the plates and the uppermost plate 6 being formed with a collar 7 to guide the said rod. At its upper end, the rod 3 has a jointed connection with the adjacent ends of the pump actuating bars 8 and 9 which extend in opposite directions alongside of the rail, and said bars are slotted at their outer ends as indicated at 10.

Pins or bolts 11 are accommodated in the slots 10 and secure the outer ends of the bars 70 for a sliding and pivotal movement in the U-shaped brackets 12 secured to the rails 13. It is designed that the car wheels of a train passing along the track shall ride over the bars 8 and 9 and depress the same so as to 75 impart a downward stroke to the pump piston, and preferably the pump is placed at a switch on a side track that is most in use, and if possible, on the outside of the curve, so that the wheels will run on the bars 8 and 9 80 and force them downwardly, and so that as soon as one wheel is off the bars, the latter will rise and be again depressed by the succeeding wheel, so as to properly reciprocate the pump piston.

85 Figure 1 designates the air inlet pipe of the pump 1 which is preferably provided at its inlet end with a screen 15 to prevent foreign substances from being drawn into the pipe, and 16 designates the inlet check valve of the pump. 90 The outlet pipe 17 leading from the pump 1 is provided with an outwardly opening check valve 18 and is connected at its far end to the air supply tank 19 which may be located at any desired point and in proximity to the pump.

95 The air supply tank 19 may be provided with the usual pressure gage 20. Said tank is also provided with a standard 21 projecting upwardly from its top, and a link 22 is 100 connected at one end to said standard and is connected at its opposite end to a lever 23, from which the piston rod 24 depends. This piston rod carries a piston 25 at its lower end

that is mounted to reciprocate in the cylinder 26, which, at its lower end is in open communication with the interior of the tank. A weight 27 is carried in an adjustable manner 5 on the outer end of the lever 23. A rod 28 is secured at one end to the weighted lever 23 and is pivotally connected at its opposite end to the handle 29 on the plug valve 30. This valve is mounted in and controls the passage 10 through a pipe 31 which communicates at one end with the interior of the tank 19 and which extends to and has its other end in communication with one end of a cylinder 32 that is preferably supported on the lower plate 15 5. A piston 33 is mounted to reciprocate in the cylinder 32 and the rod or stem 34 of said piston projects upwardly and is connected to one of the pump actuating bars 8 and 9.

20 In the practical operation of the parts of the mechanism above described, it will be understood that a train passing along the track where the mechanism is located will depress the bars 8 and 9 to cause a downward traverse of the pump piston so as to force air into the supply tank 19. So long as the air pressure within the tank is sufficient to move the piston 25 upwardly and swing the lever 23 to the position shown in full lines 25 in Fig. 1, it is to be understood that the plug 30 will close the pipe 31. Whenever the pressure within the supply tank 19 falls below a predetermined point, insufficient to raise the piston 25, the weight of the lever 23. 30 will cause the plug 30 to turn to the open position, whereupon the air pressure within the tank will move the piston 33 upwardly and through the instrumentality of the stem 34 carry the bars 8 and 9 upwardly.

35 40 It is obvious that the motion of the pump piston may be increased, if found desirable or necessary, by positioning a walking beam or lever between the pump rod and the pump actuating bars, so as to increase the stroke of the pump to the desired extent.

From the air supply tank 19 an air supply pipe 35 leads to a controlling valve 37 that is preferably located at the switch, or at the switch and signal operating station. This 50 valve may, if desired, be boxed as indicated at 38 and secured to the underside of the switch head 39 upon which the switch stand 40 is mounted.

45 55 60 65 41 designates a switch lever or actuating rod which is mounted in the stand 40 and which is provided at its lower end with a crank 42. The switch bar 43 is connected to the said crank preferably by the wrist pin 44 of the latter. Another crank 45 is secured to said wrist pin preferably by a screw and two socketed studs 46, as shown, and said crank 45 is carried on the upper end of the valve actuating shaft 47. This shaft 47 extends downwardly into the box 38 and is 65 preferably provided at its lower end with a

70 polygonal socket designed to fit over the polygonal head of the plug 48 forming part of the valve 37 and mounted within the body thereof, as shown, to turn about a vertical axis. The body of the valve 37 is provided with two preferably straightway passages 49 and 50 that are designed to be controlled by the respective ports 51 and 52 formed in the plug 48. These ports are so arranged that when the passage 49 is open, the passage 50 will be closed and vice versa. The air supply pipe 35 is secured at one end with in one end of the passage 49, and to the other end of this passage a pipe 53 leads to the signal mechanism. A release pipe 54, 80 which may be formed of a suitably strong section of hose or rubber tubing is connected, as by the T-coupling 55 to the pipe 53 and is also connected to the body of the valve 37 at the passage 50 thereof, the said passage being the release passage of the valve and being designed to permit the release of the compressed air after the supply has been shut off, and it is desired that the signal return to what might be called its normal position. 85

90 The signals may be located at any desired distance on either side of the switch, as they are actuated by air pressure, and as an example of one form or embodiment of signal mechanism, I have illustrated the post 56 which supports a box or casing 57 provided with a bottom opening, as shown, and forming a housing for the signal proper so as to protect it from the elements and so as to allow it to move into a concealed position. A cylinder 58 is supported within the bottom of the box 57 and a piston 59 is mounted in said cylinder, the stem 60 of said piston passing upwardly through the top of the cylinder and being connected to one arm of the signal supporting lever 61 that is fulcrumed intermediate of its ends on the upper end of the post 56 to swing about a horizontal axis. 100 The rear arm of the lever 61 carries an adjustable weight, as shown, and the other arm of the lever is preferably formed with a hook 62 over which the ball of the signal lantern 63 may be caught so as to removably support 105 the lantern on the lever. 110

115 From the foregoing, it will be understood that when the switch is thrown in one direction, the plug 48 will be so turned as to admit air from the supply pipe 35 through the 120 passage 49 in the body of the valve 37 and thence through the pipe 53 to the lower end of the cylinder 58. This will result in effecting the upward movement of the piston 59 so as to rock the lever 61 in a direction to 125 carry the signal lantern 63 from its concealed position within the casing 57 to an exposed position below the bottom of the casing as illustrated by the dotted lines in Fig. 2. At such position of the plug 48, that is, when it 130

admits air from the pipe 35 to the pipe 53, it is evident that the passage 50 is closed by said plug. When the switch is thrown to the opposite position, the plug 48 is so turned as to close the passage 49 through the valve 47 and at once open the passage 50 whereupon the air pressure from the pipe 53 will be permitted to vent itself through the release branch 54 and passage 50 of the valve. 5

10 As another embodiment of signal mechanism, reference is to be had to Fig. 9, in which 56^a designates the signal supporting post, 57^a the casing, and 58^a a collapsible cylinder of leather or other material suitable 15 for the purpose, the air supply pipe 53^a opening into the lower end of said cylinder. 59^a designates the piston of said cylinder which in this form of the invention, constitutes the upper head thereof and from which the piston 20 ton rod 60^a extends upwardly as shown and is guided in the sleeve 64 projecting upwardly from the roof of the casing 57^a. The rod 60^a has a pin and slot connection with the signal supporting lever 61^a. The operation 25 of this form of signal mechanism is similar to that just above described and is believed to be obvious.

It is to be understood that the train actuating air pumping and supplying mechanism 30 is applicable to switch work as well as to the actuation of signals, and I shall now describe its relation to switch mechanism.

Fig. 3 illustrates a switch in which 65 are the stationary rails, 66 the switch points, 67 35 the guard rails and 68 the switch head. The switch bar 69 is connected to the guard rails 67 which are in turn so connected to the switch points 66 as to move therewith and said switch bar may be provided at either or 40 both ends with an extension 70 to which the hand actuated switch throwing devices (not shown) may be connected. A clamp 71 illustrated in detail in Fig. 6 is secured to the switch bar 69 intermediate of the ends of the 45 latter and said clamp carries a forked bracket 72 which is mounted to turn thereon as shown, and which carries a pin 73 designed to pass through a transverse opening at the middle of the switch locking bar 74. This 50 bar is provided at each end with a shoulder 75 designed to engage the outer side of the stationary rail 65 according as the switch is thrown to one position or the other. The switch locking rod 74 is provided with an 55 apertured ear 76 to which the pneumatically actuated switch bar 77 is connected at one end as shown. The other end of this bar 77 is pivotally connected to the piston rod 78 guided by the casting 79 secured to a side of 60 the switch head 68 and carrying at its outer end a piston 80 movable within the cylinder 81. This cylinder is connected at opposite ends to the pipes 82 and 83, respectively, said pipes being provided with the control-

ling valves 84 and 85 constructed similar to 65 the controlling valve 37 and receiving their supply of compressed air from the pipes 86 connected to a common or independent air tank (not shown).

87 designates the actuating handles for the 70 plugs of these valves 84 and 85, said valves and their actuated handles being located at any desired point, as, for instance, an operating tower, so that a single operator may control and operate a large number of 75 switches, thereby making the device when arranged as above described useful particularly in yards and other places where considerable shifting is constantly going on.

From the foregoing description in connection with the accompanying drawings, it will be seen that I have provided a very efficient and durable construction and arrangement of parts of railway switch and signal mechanism in which the pump for supplying a tank with compressed air may be effectively operated by the passage of trains over any predetermined portion of a track and in which the pumping mechanism is controlled automatically by the pressure of air 90 within the supply tank without the necessity of springs or similar contrivances to move the pump actuating bars to the upper position, and in which the signal or switch mechanism may be positively controlled by pneumatic pressure which provides that the mechanism may be easily installed and cheaply maintained, and which is not liable to get out of order, there being no bell cranks or any system of wires or rods necessary, and it 95 thereby being possible to locate the signal mechanism or the switch throwing mechanism at a considerable distance from the operator.

Having thus described the invention, what 105 is claimed as new is:

1. The combination with pneumatic switch or signal actuating mechanism, and a supply tank therefor, of an air pump operatively connected with the tank and arranged 110 to feed air therein, pump actuating bars operatively connected to the plunger of said pump, and arranged to be moved downwardly by the passage of a train over the track to cause the traverse of the pump rod 115 in one direction, and pneumatic means connected to the supply tank and bars, arranged to automatically move the bars in the opposite direction, as and for the purpose set forth.

2. The combination with pneumatic switch or signal mechanism, of an air supply tank therefor, an air pump arranged to feed air into the tank, bars operatively connected to the plunger of the pump and designed to 125 be moved in one direction by the passage of a train over the track so as to actuate the pump, an air cylinder, a piston mounted

- therein operatively connected to one of said bars, a connection between said cylinder and the tank, and means for automatically opening said connection between the tank and cylinder upon the depletion of the compressed air within the tank.
3. The combination with pneumatic switch and signal actuating mechanism, of an air supply tank therefor, an air pump arranged to feed air into the tank, bars operatively connected to the pump and arranged to move in one direction by the passage of a train over the track, a cylinder, a piston mounted within the cylinder and connected to one of said bars to raise the same, a pipe connection between said cylinder and the tank, a valve designed to open and close the said pipe connection, a cylinder connected to the tank and communicating with the interior thereof, a piston mounted in said last named cylinder, a lever to which said piston is operatively connected, and a connection between said lever and the valve of the said pipe connection, the parts being arranged so that the lever will open the valve when the piston of the tank cylinder moves inwardly and will close said valve when said piston is forced upwardly.
4. The combination with pneumatic switch and signal actuating mechanism, an air supply tank therefor, an air pump arranged to feed air into the tank, bars operatively connected to the pump to actuate the same and designed to be moved in one direction by the passage of a car over the track, a cylinder, a piston mounted in said cylinder and operatively connected to one of said bars to move the same upwardly, a pipe connection between said cylinder and the tank, a turning valve mounted in said pipe connection and adapted to open and close the latter, a handle secured to said valve, a rod connected to said handle at one end, a weighted lever mounted on the tank and connected to the other end of said rod, a cylinder mounted on the tank and in communication with the interior thereof, and a piston mounted within said cylinder and having a connection with the said lever.
5. In pneumatic switch or signal actuating mechanism, a source of supply of compressed air, a supply pipe connected thereto, a controlling valve formed with two passages to one of which the supply pipe is connected, a pipe leading to the switch or signal mechanism and adapted to convey compressed air thereto to actuate the switch or signal, said pipe being connected to the same passage of the valve as the air supply pipe so as to receive air from said supply pipe through said passage, a release branch pipe connected to the pipe leading to the switch or signal mechanism and also connected to the other passage of said valve, and a plug mounted in the body of said valve and provided with ports controlling the passages thereof, respectively, the ports of said plug being arranged to close one of said passages when it opens the other.
6. In pneumatic switch and signal mechanism, a switch stand, a switch actuating rod mounted on said stand and provided with signal mechanism, a pipe leading thereto, means for actuating the signal upon the admission of compressed air to said pipe, a valve the body of which is formed with two passages to one of which said pipe is connected, an air supply pipe connected to the same passage, a source of supply of compressed air for said supply pipe, a release branch connected to the first named pipe and also connected to the other passage of the valve body, a plug mounted in said valve body and formed with ports arranged to open one of said passages and close the other, and vice versa, and an operative connection between said plug and the switch actuating rod.
7. In pneumatic switch and signal mechanism a switch stand, a switch rod mounted therein and formed with a crank, a switch bar connected to said crank, another crank connected to said first named crank, a shaft connected to said last named crank, and arranged to be turned thereby, a source of supply of compressed air, a supply pipe leading therefrom, a valve, the body of which is formed with two passages to one of which the said supply pipe is connected, a pipe connected to the same passage and leading to the signal mechanism, signal mechanism arranged to be actuated by the admission of compressed air into the last named pipe, a release branch connected to the other passage of the valve body and arranged to permit the exhaust of air from the pipe leading to the signal mechanism, and a plug mounted in the valve body and provided with ports so arranged as to close one of said passages when the other is open, said plug being connected to said shaft.
8. A mechanism of the character described the combination of movable switch points, a switch bar arranged to move laterally as the points swing, a clamp connected to said switch bar, a switch locking rod mounted to rock on said clamp and provided with shoulders arranged to engage alternately the stationary rails of the switch, a pneumatically actuated switch bar, the switch locking rod being formed with an ear to which one end of said pneumatically actuated switch bar is connected, a piston rod connected to the other end of said last named switch bar, a piston secured on said rod, a cylinder within which said piston is mounted to reciprocate, and pneumatic means for controlling the admission of air into the cylinder on opposite sides of said piston, whereby to move the piston in one direction or the opposite.

9. The combination with movable switch points and stationary rails of the switch, of a switch bar movable with said switch points, a clamp secured to said switch bar, a bracket mounted on said clamp, a switch locking rod provided on opposite ends with shoulders designed to engage the stationary switch rails alternately and having a locking connection with the said bracket and formed with an

apertured ear, and means for moving said 10 last named switch bar.

In testimony whereof I affix my signature in presence of two witnesses.
